FACING PANEL FOR A FIRE EXTINGUISHER CABINET

Samuel Shone, 1461 S. Canfield Ave., Los Angeles, Calif.

Filed Apr. 20, 1964, Ser. No. 79,578

Term of patent 14 years

(Cl. D16—2)

FIG. 1 is a perspective view of a facing panel for a fire extinguisher cabinet showing my new design.

FIG. 2 is a side elevation of the facing panel for a fire extinguisher cabinet shown in FIG. 1.

FIG. 3 is a front elevation of the facing panel for a fire extinguisher cabinet shown in FIG. 1.

FIG. 4 is a rear elevation of the facing panel for a fire extinguisher cabinet shown in FIG. 1.

FIG. 5 is a plan view of the facing panel for a fire extinguisher cabinet shown in FIG. 1.

FIG. 6 is a perspective view of a modified form of a facing panel for a fire extinguisher cabinet showing my design.

FIG. 7 is a side elevation of the facing panel for a fire extinguisher cabinet shown in FIG. 6.

FIG. 8 is a front elevation of the facing panel for a fire extinguisher cabinet shown in FIG. 6.

FIG. 9 is a rear elevation of the facing panel for a fire extinguisher cabinet shown in FIG. 6.

FIG. 10 is a perspective view of a modified form of facing panel for a fire extinguisher cabinet showing my design.

FIG. 11 is a plan view of the facing panel for a fire extinguisher cabinet of FIG. 10.

The dotted lines shown in the figures are not part of the design but are shown for illustrative purposes only.

I claim:

The ornamental design for a facing panel for a fire extinguisher cabinet, substantially as shown and described.
